UNITED STATES PATENT OFFICE.

BURDETTE STUMP, OF DENVER, COLORADO.

PHONOGRAPH.

Application filed July 29, 1922. Serial No. 578,347.

This invention relates to improvements in phonographs and its primary object is to produce an instrument in which the sounds reproduced by the vibratory motion of a diaphragm actuated by the movement of a stylus through the grooves of a phonographic record, are transmitted to the ear, in clear, mellow and distinct tones.

Another object of the invention is to provide a phonograph in which the reproduced sounds are enhanced by reenforcement of the vibrations of the diaphragm, and still further objects reside in details of construction and a novel arrangement of parts, fully set forth in the following description with reference to the accompanying drawings.

In the drawings in the several views of which like parts are similarly designated,

Figure 1 represents a partially sectional front elevation of my improved phonograph;

Figure 2, a vertical section through the instrument, partially in elevation, taken on the line 2—2 in Figure 4;

Figure 3, a transverse, horizontal section on the line 3—3, Figure 2;

Figure 4, a vertical section taken on the line 4—4, Figure 2;

Figure 5, a section along the line 5—5,

Figure 4 drawn to an enlarged scale;

Figure 6, a horizontal section along the line 6—6, Figure 4; and

Figure 7, a fragmentary section on the line 7—7, Figure 4.

The most important and essential feature of the invention resides in the provision of a hollow metallic element which is connected with a vibratory sounding board over which the sound waves move while being propagated through the air; another feature is to so arrange the conduit through which the sound produced by the vibrating diaphragm, passes to the tone-chamber of which the sounding board is a part, that the motion of each sound wave is transmitted to the walls of the chamber and through said walls to certain auxiliary metal elements which by sympathetic vibration aid in its amplification and purification; and still another feature is to provide means for limiting the vibratory motion of the walls of the instrument and thereby steady and sustain the tones produced therein by weight and advantageously applied reenforcements.

Referring now to the drawings, the reference character 2 designates a phonograph casing or cabinet of conventional size and

form which by means of partitions 3, 4 and 5 is divided into a motor chamber 6, a primary tone chamber 7 and a secondary tone chamber 8.

The walls of the casing are made of comparatively heavy wood to prevent excessive vibration, and the bottom is for the same purpose, weighted by means of a metal plate 9.

A motor 10 in the chamber 6 is operatively connected with a rotary turntable 12 upon which the phonographic records are supported.

A rotary hollow tone arm 13 and a reproductive sound box 14 at the free end thereof, carry the stylus 15 which co-operates with the indentations of the record to reproduce the sound.

Both the arm 13 and the sound box 14 are of the usual type and they are supported upon a cork plate or washer 16 which serves as a cushion and tends to absorb the metallic noises of the arm, reproducer box and stylus.

The hollow tone arm communicates with a conduit 17 which passes through the motor chamber and connects at its lower end with an elbow 18 constituting the throat of the primary tone chamber.

The latter is composed of four diverging sides of which the before mentioned partitions 4 and 3 are the upper and lower ones.

An upright partition 19 in the rear end of the tone chamber provides a compartment 20 in which the elbow is fitted.

It is an important feature of the invention that this elbow touches the four walls of the compartment as clearly shown in Figure 5, since by these means the vibrations of the sound waves are communicated to the walls of the chamber and indirectly to the walls of the cabinet.

The partition 19 has an opening to receive the open end of the metal throat and the latter is formed with a number of flutes or corrugations 18^a as best shown in Figure 5, which give direction to the tone waves and prevent them from crowding or blending together.

The lower wall 3 of the tone chamber is loose at its forward edge and constitutes a vibrating sounding board which performs an important function in the clear reproduction of the sounds, as will hereinafter be more fully described.

The sounding board is braced at its rearward end by a metal plate 21 which prevents

excessive vibration and sustains and steadies the tones as they pass through the metal throat, and a similar plate 22 is placed inside the motor chamber between the partitions 4 and 5 for the same purpose.

The funnel-shaped primary sounding chamber, the upright sides of which are designated by the numerals 23 and 24, is open at the front of the casing and its opening 10 may, if so desired, be covered by a non-metallic ornamental screen 25.

Loosely suspended from the lower side 3 or sounding board of the primary sounding chamber inside the lower and secondary 15 chamber, is a hollow metal vessel 26 which in the construction shown in the drawings, is made in the form of a cylindrical kettle. The vessel is suspended from a hook in the center of the sounding board by means of a 20 non-metallic strap 27, preferably made of leather, and its movement is restricted by two spiral springs 28 which connect its bottom portion at diametrically opposite points, with the side walls of the casing.

25 When in the operation of the instrument, the sounding board vibrates by the tone waves propagated from the throat through the gradually widening tone chamber, its motions are transmitted to the metal vessel 20 which being capable of independent vibration, enhances the sound, and greatly improves the character of the tones by a mellowing and separative effect and the absorption of foreign noises.

30 An inverted gong 29 supported on the bottom of the vessel serves to adapt it to instruments of different sizes and tone-reproducing qualities, it having been found that by varying the size of this gong or by placing 40 two or more on the same support, the vessel may be attuned to any instrument.

It is essential that the hollow metal body be suspended from the lower wall of the tone chamber, free for independent vibration 45 and through the medium of a non-metallic member which prevents diffusion of the transmitted tones.

It will be evident that the tone waves passing through the throat of the tone chamber not only vibrate the walls thereof by 50 their direct contact with the throat but also indirectly vibrate the walls of the casing. These vibrations are taken advantage of to further improve the character of the reproduced sounds, by equipping the walls with 55 metallic resonant elements, of a type similar to that connected with the bottom of the tone chamber.

These elements may be of different form,

construction and proportions, according to 60 the size and character of the instrument to which they are applied and it should be understood that their design and arrangement as shown in the drawings, may be varied to 65 accord with different instruments, without departing from the spirit of my invention.

In the drawing, two bells 30, a gong 31, an apertured tube 32 and a spiral spring 33 are connected with the rear wall of the instrument, it being apparent that the spring 70 75 performs to some extent the function of a hollow body.

A gong 34 is fastened to one of the side walls of the cabinet, a double gong 35 is applied to the opposite wall of the same, a similar arrangement of gongs 36 is attached to the upper wall of the primary tone chamber inside the motor chamber and a pair of heavier gongs 37 is supported on the heavy 80 metal-weighted bottom of the casing, which is less subject to vibration.

Aside from their purifying, amplifying and mellowing effect upon the sound waves produced in the operation of the instrument, the different parts and features of construction hereinabove described, co-operate to 85 separate and classify the tones and thereby prevent the undue blending and unharmonious mingling often observed in phonograph instruments of ordinary construction.

Having thus described my improved phonograph, I desire it understood that variations in the arrangement and construction of its co-operative parts, other than those hereinbefore referred to, may be resorted to 90 within the scope of my invention, as defined by the hereunto appended claim.

What I claim and desire to secure by Letters Patent is:

In a phonograph, a cabinet provided in its upper portion with a tone chamber extending from front to rear and tapered longitudinally, said tone chamber being composed of top, bottom and side walls, the bottom wall having its front edge free and constituting a sounding board, a resonator consisting of an open cylindrical metallic vessel suspended at its open end from the bottom wall of the tone chamber and arranged in spaced relation with the walls and bottom of the cabinet, and opposite spiral springs connecting the closed bottom of the resonator with the walls of the cabinet at diametrical- 100 105 110 115 115

In testimony whereof I have affixed my signature.

BURDETTE STUMP.
